UNITED STATES PATENT OFFICE.

ARTHUR VAN HOUWELING, OF PELLA, IOWA, ASSIGNOR TO THE PELLA AUTOMATIC STRAW STACKER CO., OF PELLA, IOWA.

STRAW-STACKER.

SPECIFICATION forming part of Letters Patent No. 684,531, dated October 15, 1901.

Application filed August 21, 1900. Serial No. 27,557. (No model.)

To all whom it may concern:

Be it known that I, ARTHUR VAN HOUWELING, a citizen of the United States, residing at Pella, in the county of Marion, State of Iowa, have invented certain new and useful Improvements in Straw-Stackers, of which the following is a specification.

This invention relates to that class of straw-stackers in which the straw is carried upon an endless conveyer and in which the outer end portion of the conveyer-frame is hinged to be capable of inclining downwardly with relation to the body portion of the conveyer-frame.

15. My objects in this invention are, first, to provide an improved stacker-frame of this class in which the weight of the conveyer is carried upon the main conveyer-frame to the end that the hinged outer portion of the conveyer-frame may be made light in weight and inexpensive in construction.

A further object is to provide means whereby this folding outer end may be adjusted vertically with relation to the main conveyer-frame from a point at the base of the main conveyer-frame and at the same time said folding outer end may be drawn close up under the main frame from the same position.

25. A further object is to provide improved means whereby the main conveyer-frame may be raised and lowered by an operator standing upon the ground at the side of the stacker.

30. A further object is to provide means whereby the conveyer is driven from two points—to wit, the upwardly-moving portion thereof at the base of the stacker and the downwardly-moving portion at the base of the stacker—which means shall be of simple, strong, durable, and inexpensive construction, whereby 40 excessive strains are avoided upon the conveyer-chains at one point.

35. My invention consists in certain details in the construction, arrangement, and combination of the various parts of the device, whereby 45 by the objects contemplated are attained, as hereinafter more fully set forth, pointed out in my claims, and illustrated in the accompanying drawings, in which—

40. Figure 1 shows a side elevation of the complete stacker. Fig. 2 shows a transverse 50 sectional view through the stacker-frame to

illustrate the means for winding up the ropes or cables which control the elevation of the stacker-frame. Fig. 3 illustrates diagrammatically the means for driving the endless 55 conveyer from two points. Fig. 4 shows a top or plan view of the complete machine. Fig. 5 shows a sectional view of one side of the conveyer-frame, showing stub-shaft.

Referring to the accompanying drawings, 60 I have used the reference-numeral 10 to indicate the horizontal portion of the stacker-frame.

11 indicates that portion of the stacker-frame pivoted to the horizontal portion, to 65 extend upwardly and rearwardly therefrom. This frame is hinged to the part 10 in the ordinary way. The outer end portion of the said frame 11 is supported as follows: Idlers 12 are mounted on the sides of the frame at 70 its top portion, and a pulley 13 is swiveled to a support 14, which support is connected with the threshing-machine. Near the base of the part 11 is a shaft 15, rotatably mounted in suitable bearings and having at one end a crank 16. 75 On the opposite end portions of the shaft 15 are the pinions 17, which pinions are meshed with the cog-wheels 18. These cog-wheels 18 are supported upon the stub-axles 19, and connected with the cog-wheels 18 are the drums 80 20. It is obvious that upon a rotation of the crank 16 the said drums will be turned. Fixed to the drums 20 are the ends of a cable or rope 21. This cable is passed over the idlers 12 and around the pulley 13. Hence it 85 is obvious that by manipulation of the crank 16 the ends of the rope or cable 21 are wound upon the drums 20 and the stacker-frame 11 is raised. This may be done by an operator standing upon the ground at one side of the 90 stacker.

In the part 10 of the stacker-frame two shafts 22 and 23 are rotatably mounted, the one above the other. On the shaft 22 are the sprocket-wheels 24 to mesh with the conveyer-chains, which chains are indicated by the numeral 25, and on the shaft 23 are the sprocket-wheels 26, also in mesh with the lower portion of the conveyer-chain. These two shafts 22 and 23 are driven as follows: 100 On the ends of the shafts 22 and 23 are the cog-wheels 27 and 28, meshed with each other.

By this means it is obvious that the conveyer chains will be driven by power applied to the downwardly-moving part of the conveyer and also to the upwardly-moving part. This arrangement will readily take up the slack in the downwardly-moving portion of the conveyer and prevent the excessive strains to the conveyer occasioned by applying power thereto at one point only.

10 To the outer end portion of the stacker-frame 11 I have pivoted an auxiliary frame 31 by means of the hinges 32, and attached to this frame 11 I have pivoted an auxiliary frame 31 by means of the hinges 32, and attached to this frame 31 is an upwardly and rearwardly projecting arm 33, supported by braces 34 and having a rope or cable 35 attached to its top portion. This rope or cable 35 is wound upon a drum 36, which drum is fixed 20 to a shaft mounted in the machine-frame and bearing the cog-wheel 37. A gravity-pawl 38, mounted on the side of the stacker-frame, is provided to engage this cog-wheel 37, and the said cog-wheel is driven by means of a 25 pinion 39, attached to the crank-shaft 40. This cable-winding device is similar in construction to the one before described. Hence a detailed description of its construction is deemed unnecessary. On the outer end of 30 the frame 31 is a shaft 41, having fixed thereto the sprocket-wheels 42, over which the conveyer-chains 25 travel. I have mounted in suitable bearings at the upper end of the frame 11 a shaft 43 having thereon the sprocket- 35 wheels 44, over which the conveyer-chains travel. I have also mounted on the lower surface of the upper end portion of the frame 11 the brackets 45, and in these brackets the shaft 46 is supported, bearing the sprocket- 40 wheels 47. The returning portion of the conveyer 25 passes over these sprocket-wheels 46. By this means it is obvious that the frame 31 is provided with a conveyer traversing its entire length, and, furthermore, this frame 45 31 may be moved into any position with relation to the frame 11 without affecting the operation of the conveyer. By thus attaching the idlers for supporting the conveyer-frame 11 it is obvious that all of the weight of the 50 conveyer is supported upon the frame 11 and that on this account the extension or auxiliary frame 31 may be made light in weight and cheap in construction. It is further obvious that by placing the arms 33 at the angle 55 shown the conveyer-frame 31 may be raised and lowered to any desirable position with relation to the frame 11 by a manipulation of the crank-shaft 40. Then when it is desired

to fold up the frame 31 the frame is allowed to drop to a position where it depends straight 60 downwardly from its hinge-joint, and obviously if the cable 35 is wound up when the conveyer-frame is at this angle, the frame 31 will be drawn to a position directly under the frame 11. Thus it may be readily and 65 quickly folded up to occupy a minimum of space and held to a position close to the frame 11.

Having thus described my invention, what I claim, and desire to secure by Letters Patent of the United States therefor, is—

1. In a straw-stacker, the combination of a pulley, means for supporting same from a threshing-machine, a stacker-frame pivotally connected at its lower end to move in a vertical plane, two idlers attached to the sides of the stacker-frame near its top, two drums mounted on the stacker-frame near its lower end, a rope or cable wound upon said drums at its ends, passed around said idlers, and 75 also around said pulley, and means for winding up the drums, substantially as, and for the purposes stated.

2. In a straw-stacker, the combination of a support designed to be connected with a threshing-machine, a pulley attached to said support, a stacker-frame pivotally mounted at its lower end, to swing in a vertical plane, idlers mounted on the sides of the stacker-frame near its top, a crank-shaft 15 mounted 90 upon the stacker-frame near its lower end, pinions 17 on said crank-shaft, cog-wheels 18 in mesh with said pinion and supported on the opposite sides of the stacker-frame, drums 20 connected with the cog-wheels 18, and a 95 rope, or cable, with its central portion passed around the said pulley, then passed around the said idlers, and having its ends wound upon said drum, substantially as, and for the purposes stated.

3. In a straw-stacker, the combination of a stacker-frame, a shaft mounted therein near the base of the frame, sprocket-wheels on the end portions of the shaft, two short shafts above said shaft, each of said short shafts 105 having a sprocket-wheel, cog-wheels on the ends of said shafts, those of the upper shafts being meshed with those of the lower shaft, and a conveyer having sprocket-chains at its sides, passed under the upper sprocket-wheels 110 and returning under the lower sprocket-wheels, for the purposes stated.

ARTHUR VAN HOUWELING.
